ROLL-TOP DESK

Jack L. Beavers, Boulder, Colo., assignor to Design Products, Inc., Boulder, Colo.

Filed Oct. 22, 1969, Ser. No. 19,665

Term of patent 14 years

Int. Cl. D6—01

U.S. Cl. D33—7

FIG. 1 is a rear perspective view of a roll-top desk showing my new design;

FIG. 2 is a front perspective view thereof;

FIG. 3 is a top plan view;

FIG. 4 is a rear elevational view;

FIG. 5 is a front elevational view; and

FIG. 6 is a side view.

I claim:

The ornamental design for a roll-top desk, as shown.
